(57) CLAIM

The ornamental design for a tent for kids, as shown and described.

DESCRIPTION

FIG. 1 is a front elevation view of a tent for kids showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is an enlarged detail view of the stars/snowflakes thereof from the roof thereof, seen at an angle on the roof;

FIG. 9 is an enlarged detail view of the castle thereof;

FIG. 10 is an enlarged detail view of the central star thereof;

FIG. 11 is an enlarged detail view of a group showing all the types of snowflakes thereof seen from a straight point of view; and,

FIG. 12 is an enlarged detail view of a group of the snowflakes thereof, curved lines thereof, and circles thereof, shown on a vertical column of the tent.

The dot-dash lines of FIG. 1 and FIGS. 8-12 indicate the portions of FIG. 1 that are shown in enlarged detail views in FIGS. 8-12.

1 Claim, 12 Drawing Sheets
